NAIL AND CUTICLE CONDITIONING DEVICE

Marcella A. Brandt, St Paul, Minn.

Application July 13, 1939, Serial No. 284,221

3 Claims. (Cl. 128—157)

This invention relates to a device for treating the finger nails and cuticle adjacent the nails. It is now a very common practice for persons, particularly women, to have polish applied to their 5 nails. This polish usually contains a coloring matter. Due to the application of this polish the nails become unduly brittle and are thus easily broken or split and thus marred. It is recommended by manicurists and other authorities to soften the nails and cuticle by applying 10 a softening agent, such as an oil, thereto. Such a softening agent to be effective must be left in contact with the nails for quite a period. A good time to apply such a softening agent is at 15 night. It is difficult, however, to keep such an agent in contact with the nails and an oil such as commonly used will soil the bed clothes and night clothes.

It is an object of this invention to provide a 20 very simple and efficient device by means of which a softening agent can be applied to the nails and cuticle so as to be quite effective without any danger of the softening agent coming in contact with the bed linen or other bed clothes. 25 It is a further object of the invention to provide a device for applying a softening agent to the finger nails and cuticle comprising a sleeve adapted to receive the finger and having provision by means of which a body of absorbent 30 material may be placed therein and easily adjusted into proper position.

It is also an object of the invention to provide a device for softening the nails and cuticle comprising a sleeve adapted to receive the finger and 35 having an opening at one side adjacent its end formed between overlapping layers of material, through which an absorbent material may be inserted and/or adjusted.

These and other objects and advantages of 40 the invention will be fully set forth in the following description made in connection with the accompanying drawing in which like reference characters refer to similar parts throughout the several views and in which:

45 Fig. 1 is a perspective view illustrating the device and the manner in which the absorbent material is adjusted over the nail;

Fig. 2 is a perspective view of the device;

50 Fig. 3 is a central vertical section through the device; and

Fig. 4 is a view similar to Fig. 3 showing the finger of the wearer in the device with the absorbent material in place.

55 Referring to the drawing, a device is shown comprising a sleeve or stall 10 which is of gen-

eral cylindrical shape having a closed end 10a and being arranged to receive the finger of the wearer. At the top side of the device or the side overlying the finger nail the device has a layer of material 10b having a free edge 10c 5 some distance from the closed end of the device. The device also has a layer of material 10d which extends under the layer 10b for some distance so as to be overlapped by layer 10b and layer 10d has a free edge 10e some distance from the edge 10c. The layers 10b and 10d extend substantially halfway around the device and as shown to a seam 11. It will thus be seen that there is an opening 12 between layers 10b and 10d into the sleeve 10. Said sleeve 10 is shown as provided with a hem 10f at its open end and as having a hem at the edge 10c. The sleeve 10 is made of moisture-proof material, preferably of light weight. One material which has been found to be very satisfactory in practice is rubberized 20 silk.

A body of absorbent material 13 is provided and this may be cotton or other similar material. The material 13 is saturated with the oil or softening agent to be applied to the nails and cuticle. 25 The wearer can insert the finger into the sleeve and the material 13 can then be inserted through opening 12 by the use of an orange stick or other implement 15 and the material can be nicely adjusted over the nail 14a of the finger 14 by inserting the end of the implement through the opening 12. The material 13 being disposed over the nail and cuticle the softening agent is effectively applied. The device can be worn during the night and there will be no chance for the 30 oil to get out and soil the bed clothes or night clothes of the wearer. If preferred the material 13 can be placed in the sleeve before the finger is inserted therein and the material will then be adjusted and disposed in proper position by 35 inserting the implement 15 through the opening 12. The sleeve 10 and the material 13 can be very readily removed when desired.

From the above description it will be seen that I have provided a very simple and efficient device 45 for applying a softening agent to the finger nails and cuticle. The device is very simple and can be easily and inexpensively made. Its use is very convenient and the oil or other softening agent can be applied to the nails and cuticle without 50 objectionable incidents or results. The nails are effectively softened without the necessity of taking time for the operation in the daytime and without inconvenience.

It will, of course, be understood that various 55

changes may be made in the form, details, arrangement and proportions of the parts, without departing from the scope of applicant's invention, which generally stated, consists in a 5 device capable of carrying out the objects above set forth, in the parts and combinations of parts disclosed and defined in the appended claims.

What is claimed is:

- 10 1. A device for treating the finger nails and/or cuticle comprising a sleeve made of quite flexible waterproof material and constructed and arranged to extend the length of the wearer's finger, said sleeve being of substantially uniform diameter and being open at one end and closed at 15 the other, a body of absorbent material disposed in the closed end of said sleeve adapted to overlie the finger nail, said sleeve having an opening extending transversely thereof at its top or finger nail side spaced from said body of material toward the open end of said sleeve through which opening said material may be placed and through which a tool may be inserted to adjust said material.
- 20 2. A device for treating the finger nails comprising a sleeve constructed and arranged to extend the length of the wearer's finger, the same being made of quite flexible moisture-proof ma-

terial being of substantially uniform diameter and having an open end and a closed end, said closed end being adapted to receive a body of absorbent material for overlying the finger nail, said sleeve having overlapping layers at its top or finger nail side extending a short distance longitudinally thereof and spaced some distance from the closed end of said sleeve, the transverse edges of said overlapping layers being free so that an opening is formed into said sleeve between said layers, through which opening said absorbent material may be placed and adjusted. 5

10 3. A device for treating the finger nails comprising a sleeve constructed and arranged to extend the length of the wearer's finger, said sleeve being made of quite flexible waterproof material having one end open and its opposite end closed and having an opening thereinto at its top or finger nail side, which opening extends longitudinally some distance of said sleeve between layers 20 of material forming said sleeve, the closed end of said sleeve being adapted to receive a body of absorbent material which may be inserted through said opening and adjusted over the nail of the wearer by a tool inserted through said opening. 25
